GARMENT SUPPORTER

Michael Hawie, Greens Farms, Conn., assignor
to The Hawie Manufacturing Co., Bridgeport,
Conn.

Application December 2, 1935, Serial No. 52,576

2 Claims. (Cl. 24—245)

This invention relates to improvements in garment supporters and more especially to novel means for fastening a button-tab member to the loop member of such a supporter.

5 The primary purpose of the invention is to secure the tab to the loop without weakening either.

A further object is to provide fastening means by which the tab is secured to the loop in such a 10 way as to reinforce rather than weaken the tab.

Another object is to supply fastening means whereby the tab may be secured to the loop by the same member which connects the loop to the eye of the garment supporter.

15 A still further object is to provide novel fastening means for securing the tab to the loop in a simple, inexpensive and durable manner.

With the foregoing objects outlined and with other objects in view which will appear as the description proceeds, the invention consists in the 20 novel features hereinafter disclosed in detail, illustrated in the accompanying drawing and more specifically set forth in the appended claims.

In the drawing:

25 Fig. 1 is a front elevation of my improved structure.

Fig. 2 is a sectional view of the same, taken on the line 2—2 of Fig. 1.

Fig. 3 is a rear elevation with the tab in extended position.

Figs. 4 and 5 are an elevation and a side edge view respectively of the tab.

25 Fig. 6 is a sectional view of a detail showing the reinforced end of the tab in position to be clamped by the fastening member.

Fig. 7 is a similar view illustrating the parts after the fastening member has been closed to clamp the reinforced end of the tab.

Referring to the drawing 8 designates a conventional metal loop member having a cross-bar 9 at its upper end which is secured to a metal eye 10 by means of a metal fastening member 11. The latter is bent to provide an upper curved portion 12 which partially surrounds the lower bar 13 of the eye to form a hinged joint at this point. The medial portion of the fastening member is also bent to form a lower tubular portion 14 hinged to the bar 9 of the loop. The end 15 of the fastening member is of curved or arc shaped 40 to form a clamping lip for a purpose hereinafter described.

The button tab member 16 may be made of any suitable material. For example, it may be formed of a strip of textile tape provided at one end with a rubber button 17 and at its opposite end with

a reinforced transverse shoulder 18. The parts 17 and 18 may be secured to the tape by vulcanizing or the like.

In assembling the parts the reinforced shoulder 18 is placed between the bar 13 and the lip 15 and then when the latter is moved toward the bar it will cause the lip to be compressed and to be clamped to bar 13. Owing to the curved shape of the lip, its end forms an edge to bite into the tab while the other portion of the lip furnishes 10 a cavity to receive a part of the thickened shoulder of the tab. When the joint is complete it will be understood that the distance between the end of the lip and the other end of the fastening member is less than the thickness of 15 the shoulder and consequently the latter cannot be pulled out of the space between the lip and bar 13.

From the foregoing it will be understood that the assemblage is such as to prevent the slipping of the tab from the loop and to also prevent 20 injury to the fabric forming the body of the tab.

While I have disclosed what I now consider to be a preferred embodiment of the invention in such manner that it may be readily understood 25 by those familiar with such articles, it is manifest that changes may be made in the details disclosed without departing from the spirit of the invention as expressed in the claims.

Having fully described my invention what I 30 claim as new and desire to secure by Letters Patent, is:

1. A garment supporter structure comprising a first member having a bar and a second button tab member, the latter being provided at one 35 end with a reinforced shoulder, and a fastening member having one of its ends hinged to said bar, the reinforcing shoulder extending into the fastening member between said bar and the other end of the fastening member, the last men- 40 tioned end of the fastening member being arc shaped in cross section and forming a cavity receiving said shoulder, the ends of the fastening member forming a restricted throat through which the tab extends, said throat being of less 45 width than the thickness of the shoulder to prevent the latter from being withdrawn from the cavity.

2. A garment supporter structure comprising a loop member having an upper bar, an eye hav- 50 ing a lower bar, and a button tab member provided at one end with a reinforced shoulder, a fastening member having one of its ends hinged to the lower bar of said eye and an intermediate portion forming a loop hinged to the upper bar 55

of said loop member, the reinforced shoulder extending into the fastening member between the lower bar of said eye and the free end of the fastening member, the last mentioned end of the fastening member being arc shaped in cross section and forming a cavity receiving said shoulder,

the ends of the fastening member forming a restricted throat through which the tab extends, said throat being of less width than the thickness of the shoulder to prevent the latter from being withdrawn from the cavity.

MICHAEL HAWIE.
